UNITED STATES PATENT OFFICE.

WALRAM S. BROWNE, OF BROOKLYN, NEW YORK.

ELECTRIC-RAILWAY SWITCH.

SPECIFICATION forming part of Letters Patent No. 687,475, dated November 26, 1901.

Application filed June 2, 1898. Serial No. 682,315. (No model.)

To all whom it may concern:

Be it known that I, WALRAM S. BROWNE, a citizen of the United States, residing at Brooklyn, in the city and State of New York, have 5 invented an Improvement in Electric-Railway Switches, of which the following is a specification.

In electric railways it has been proposed to move the switch point or tongue by an electromagnet, the tongue itself being the armature of the magnet; but in cases where the tread of the switch-rail on one side of the tongue, and the guard on the other have formed the pole-pieces of the electromagnet 15 the energy for moving the switch-tongue is dispersed and unreliable, and this difficulty is augmented by the liability of forming an opposite pole in some other part of the switch.

In my present invention electromagnets 20 whose pole-pieces are separate and distinct from and not a part of the switch piece or casting are applied at opposite sides of a switch-point. One or more magnets may be used on each side of the tongue; but the magnets on 25 one side are separate and distinct from those on the other side, and the poles of the magnets are brought up adjacent to the opposite sides of such switch-tongue, and the poles on one side may be directly opposite those on 30 the other or more or less distant, and these poles are insulated from the tongue, the bed-plate, and the tread and guard rails, so that the magnetic energy is concentrated in the pole-pieces of the electromagnets.

35 In Letters Patent No. 593,389, granted to me November 9, 1897, a circuit arrangement is represented for directing the current from the trolley-wire to the electromagnets that move the switch. In some instances there is 40 a risk of the switch turning or becoming displaced after it has been moved by the action of the magnets. I combine with the electromagnets that move the switch and the circuit connections passing to the same an electric 45 lock which directs the current through the particular magnet that has been energized for moving the switch, so as to hold the switch thereby during the time that the car is passing over such switch.

50 In the drawings, Figure 1 is a plan view representing the switch and the electromagnets for moving the same and a diagram of the

electric-circuit connections. Fig. 2 is an elevation, and Fig. 3 is a cross-section at the line 3 of Fig. 2.

The rails of the main track are indicated at A, and the rails of the turnout or branch track are illustrated at B, and the circuit connections at the trolley and at the track are substantially similar to those illustrated in 55 my aforesaid patent and will be hereinafter more fully set forth.

The switch place or base A' is advantageously made as a deep central rail or box 4, with a bottom flange 5 and with the rail or 60 tread 6 and guard-rail 8 upon the upper edges thereof and with the diverging guard 9 and rail 7 adjacent to the pivot 19 of the switch-tongue C, and the switch-tongue is adapted to being swung from contact with the interior 65 of the guard 8 to the interior of the tread 6 for directing the car upon the straight line or upon the turnout, and the bottom of this switch-tongue is supported upon the bed-plate 16 of the switch.

70 The electromagnets D and E are of suitable size and properly wound, and the current is to be directed, as hereinafter described, through the magnet E to set the switch for the branch or turnout B, and through the 75 magnet D to set the switch for the main track A.

75 The poles 12, 13, 14, and 15 of the electromagnets D and E pass loosely through mortises or openings in the rail and flange 8, in order that the poles may be insulated from 80 the metal of the switch, and such mortises are made low enough in the side of the switch to allow the pole-pieces to be below the flanges of the wheels passing along the track, without touching the pole-pieces. The insulation is advantageously accomplished by strips of 85 hard rubber or gutta-percha 17 between the pole-pieces and the steel or iron of the switch. Thus the magnetic energy is concentrated in 90 the pole-pieces of the electromagnets, and according to which circuit is closed so one magnet or the other will be energized and the switch-tongue attracted either one way or the other way; and I remark that by locating the 95 electromagnets nearly midway of the switch-tongue the pole-pieces may be very near to the tongue though out of contact with it, and in whatever position the tongue may happen 100

to be enough energy can be obtained in the electromagnets for easily moving the switch-tongue toward the magnet. The faces of the laterally-extending pole-pieces should be out 5 of contact with the surface of the switch-tongue, so that the parts will not stick, and the distance between the pole-pieces and the switch-tongue when such switch-tongue is 10 distant from the pole-pieces is comparatively little, so that the magnetism acts efficiently 15 in giving motion to the switch-point. I have shown two magnet-poles at each side of the tongue; but the number may be increased.

The electromagnets can be supported upon 15 the switch-base A' in any desired manner. I have represented insulating material 18 between the magnets and the bottom flange 5 of the switch, and they can be inclosed to protect them from injury.

20 I have described my invention as applied to railway-switches used in paved city streets, in which the moving part is usually called the "tongue;" but my improvement can be used to advantage on the other forms of 25 track-switches with "points" or "tongues."

It is usually advantageous to employ electromagnets with vertical cores and laterally-projecting pole-pieces; but I do not limit myself in this particular.

30 Usually the switch-tongue is sufficiently deep to form the armature to the electromagnets, but if too narrow the said tongue may be widened by a downward-projecting plate. The electric lock is located in whatever is 35 the most convenient place. It may be upon one of the trolley-poles adjacent to the switch or it may be adjacent to the track, and it consists of two electromagnets F and G, each of which is preferably made with two cores and 40 a keeper, as usual, and the poles face each other and have between them an armature H, and the helices of the electromagnets are wound with two wires, and the ends of these wires come double to the binding-posts 20 and 21, and one wire of the helix G extends 45 to the binding-post 22, and another wire of the helix F extends to the binding-post 23, and there is a double switch-post of plates 24 and 25 and 26 and 27, insulated from each other 50 in pairs, the plates 25 and 27 being connected together, and one end of one coil of the magnet G terminates at 24, and one end of one coil in the magnet F terminates at the plate 26, and a contact 40 upon the armature H 55 swings between these switches, and the circuit connections are made and the electric lock operates in the manner next described.

In the diagram illustrated in Fig. 1 of the 60 circuit connections, K indicates the trolley-wire, and L an insulated plate which is brought into circuit by contact with both the trolley-wire and the plate of the trolley-wheel, as in my aforesaid patent, and S represents the insulated rail thereof, and from the insulated plate L the wire 30 extends to the binding-post 22, and from the insulated rail S the wire 31 extends to the binding-post 23.

If now the car approaches the turnout in the direction of the arrow and the motorman turns off the current, so that the car runs by 70 momentum, the current passes from K L by 30 and through the magnet G, attracting the armature H and closing the circuit between 24 and 25, and the current after passing from 22 through the helix of G to 20 goes by the 75 wire 32 to the electromagnet E, and thence to the rail, energizing the magnet E and drawing the switch-point toward the main-track guard-rail 8, so as to open the switch to the curved or branch track, and as the car progresses the circuit is closed between L², which is an insulated plate, and the trolley-wire K and passes by the binding-post 28 and the circuit connections to the plate 25 and by the contact 40 on the armature H and plate 24 85 through the magnet G and wire 32 to the switch-magnet E, so as to retain the energy in such switch-magnet during the time that the car is passing fully onto the switch, after which the circuits are broken.

As set forth in the aforesaid patent, when the current is not turned off at the car it simply passes momentarily from K through L and 30 and to E; but as soon as the trolley-wheel separates from the plate L the current 95 passing from the trolley through the motor on the car goes to the insulated rail S and from there by the wire 31 to the binding-post 23 and through the magnet F to the binding-post 21 and from there by the wire 34 to the 100 magnet D and to the rail, and in so doing the switch-point is attracted and the car proceeds on the main track, and in passing through the helix F the armature H closes the circuit between 26 and 27, and as the trolley-wheel 105 comes in contact with the insulated plate L² the current passes through the same from the trolley-wire K and by 28 to 27 26 and by the circuit-coil through the magnet F to 21 and by the wire 34 to the magnet D, so as to not 110 only hold the armature H by the magnet F, but also to lock the switch by the current passing through the magnet D. It will be observed that this magnet-lock acting in connection with the insulated plate L², adjoining the trolley-conductor K, insures the locking of the switch in either one direction or the other by the current being maintained in either the magnet D or the magnet E until the car has 115 passed the switch, it being understood that the insulated contact-plate L² adjacent to the trolley-conductor K is sufficiently long to insure a continuance of the current to one magnet or the other until the last wheels of the car have passed by the switch-tongue either 125 upon the main track or upon the turnout. If the car should be stopped upon the switch or should it be found that the switch-lock has by any external influence been moved into the wrong position, the conductor or motorman can turn the same by hand into the proper position, so as to direct the current 130 to the proper magnet regardless of the position that the car may occupy upon the switch.

I claim as my invention—

1. The combination with the switch-point and the electromagnets for moving the same, of the circuit connections and an electromagnetic locking device brought into action by the pulsation of the current to one or the other of the switch-magnets, and an armature switch and connection to the trolley-conductor, whereby a current is maintained to the electromagnet that has moved the switch for holding such switch until the car has passed, substantially as set forth.
2. The combination with the magnets D and E and the switch-point moved by the same, of the electromagnetic lock composed of magnets F and G and the armature-switch moved by the same, an insulated rail through which the current passes by the motor of the car to one of the magnets, an insulated plate adjacent to the trolley-conductor by which the current passes through the trolley-wheel to the other electromagnet, and an insulated plate adjacent to the trolley-conductor by which the current passes through the trolley-wheel and the armature-switch of the locking mechanism to one or other of the electromagnets, for holding the switch-point in the position to which it has been moved for the passage of the car, substantially as set forth.
3. The combination with the switch-base and pivoted switch-point of an electromagnet having laterally-projecting pole-pieces, the switch-base being mortised for the passage of the pole-pieces and means for insulating the pole-pieces from the metal of the switch and for supporting the electromagnet with the ends of the pole-pieces near the side of the switch-point, substantially as set forth.
4. The combination with the switch-base and pivoted switch-point, of an electromagnet having laterally-projecting pole-pieces, the switch-base being mortised for the passage of the pole-pieces and means for insulating the pole-pieces from the metal of the switch, and for supporting the electromagnet with the ends of the pole-pieces near one side of the switch-point, and a second electromagnet with laterally-projecting pole-pieces passing through mortises in the switch-base, and means for insulating the pole-pieces from the metal of the switch-base and for supporting the electromagnet with the faces of the pole-pieces near the opposite side of the movable switch-point, substantially as set forth.
5. The combination in a railway-frog, with a base-plate and wing-rails, a switch-point supported and moved on the base-plate, electromagnets, cores from the electromagnets extending through apertures in the wing-rails upon opposite sides of the switch-point, and contact devices upon a moving car adapted to energize the magnets from the trolley-circuit, of an electromagnetic locking device brought into action by the pulsations of the current to one or the other of the switch-

magnets, whereby the switch-point is held until the car has passed, substantially as set forth.

6. The combination with the switch-base and pivoted switch-point, of an electromagnet having laterally-projecting pole-pieces, the switch-base adapted for the passage of the pole-pieces, means for supporting the electromagnet with the ends of the pole-pieces near the side of the switch-point, a second electromagnet and circuit connections and means for controlling the same and holding the switch-point to prevent its accidental movement, substantially as specified.

7. The combination in a railway-frog, with a base-plate and wing-rails, a switch-point supported and moved on the base-plate, electromagnets, cores from the electromagnets extending through apertures in the wing-rails and insulated therefrom, upon opposite sides of the switch-point, and contact devices upon a moving car adapted to energize the magnets from the trolley-circuit, of an electromagnetic locking device brought into action by the pulsations of the current to one or the other of the switch-magnets, whereby the switch-point is held until the car has passed, substantially as set forth.

8. The combination with the switch-base and pivoted switch-point, of an electromagnet having laterally-projecting pole-pieces, the switch-base adapted for the passage of the pole-pieces and means for supporting the electromagnet with the ends of the pole-pieces near one side of the switch-point, and a second electromagnet with laterally-projecting pole-pieces passing through mortises in the switch-base, and means for supporting the electromagnet with the faces of the pole-pieces near the opposite side of the removable switch-point, substantially as set forth.

9. The combination of a railway-frog, comprising a base-plate and wing-rails, a switch-point supported and moved on the base-plate, electromagnets, cores from the electromagnets extending through the apertures in the wing-rails upon opposite sides of the switch-point, and contact devices upon a moving car adapted to energize the magnets from the trolley-circuit, substantially as described.

10. The combination of a railway-frog, comprising a base-plate and wing-rails, a switch-point supported and moved on the base-plate, electromagnets, cores from the electromagnets extending through apertures in the wing-rails and insulated therefrom, upon opposite sides of the switch-point, and contact devices upon a moving car adapted to energize the magnets from the trolley-circuit, substantially as described.

Signed by me this 28th day of May, 1898.
